Patented Aug. 24, 1920.

Inventor:
W. A. Schuler

UNITED STATES PATENT OFFICE.

WILLIAM ANTON SCHULER, OF NEW YORK, N. Y.

DESIGN FOR A CLUTCH.

56,196.

Specification for Design.

Patented Aug. 24, 1920.

Application filed April 28, 1920. Serial No. 377,391. Term of patent 14 years.

To all whom it may concern:

Be it known that I, WILLIAM ANTON SCHULER, a citizen of the United States, and residing at New York, in the county of New York and State of New York, have invented a new, original, and ornamental Design for Clutches, of which the following is a specification, reference being had to

the accompanying drawing, forming part thereof.

The figure is a perspective view of a clutch, showing my new design.

I claim:

The ornamental design for a clutch, as shown.

WILLIAM ANTON SCHULER.
